UNITED STATES PATENT OFFICE.

JOSEPH J. SZEPE, OF PITTSBURGH, PENNSYLVANIA, ASSIGNOR TO KEYSTONE DIE AND MANUFACTURING COMPANY, OF PITTSBURGH, PENNSYLVANIA, A CORPORATION OF PENNSYLVANIA.

COIN HOLDER.

Application filed March 5, 1921. Serial No. 450,024.

To all whom it may concern:

Be it known that I, JOSEPH J. SZEPE, a citizen of the United States, residing at Pittsburgh, in the county of Allegheny and

5 State of Pennsylvania, have invented new and useful Improvements in Coin Holders, of which the following is a specification.

10 My invention relates to devices for holding coins, street-car checks, and analogous circular or disk-shaped articles so that they may be readily removed.

The object of the present invention is to simplify said devices so that the various parts except the springs may be stamped 15 out of the fewest possible number of pieces of sheet-metal. In the preferred form of my invention I employ only two pieces of sheet-metal for the body and cover, two sheet-metal cupped disks or plungers for 20 supporting the said articles and two springs for yieldingly supporting the disks and clamping the articles to the holder. Another object is to provide interlocking means formed preferably integral with the body 25 and cover to hold the assembled parts in proper relative position. Another object is to provide the cover with suitable means for spacing it from the bottom of the body and preferably to employ the spacing means 30 to limit the distance the said articles can be pushed into the holder and to serve as a guide for the article-clamping plunger.

Referring to the accompanying drawing, Fig. 1 is a perspective view of the coin-holder complete; Fig. 2, a top plan view of the same; Fig. 3, a longitudinal vertical section on the line III—III of Fig. 2; Fig. 4, a transverse section of Fig. 2 on the line IV—IV; Fig. 5, a perspective view of the 40 cover member; and Fig. 6, a horizontal section on the line VI—VI of Fig. 3.

On the drawing, 1 designates the body of the holder and 2 the cover thereof, each made of sheet-metal drawn or bent from 45 suitably-shaped blanks. The body has the bottom 3 having integral therewith the sides 4, and ends 5 arranged at right angles with the bottom 3. The sides 4 are flat and parallel but the ends 5 are rounded outwardly in semicircular shape corresponding to that of the article to be held by the holder. The sides of the body are spaced apart a distance equal to the diameter of the coins to be inserted into the holder.

55 The cover 2 has its ends rounded to cor-

respond to the curvature of the ends 5. At each end of the cover is an oval hole somewhat smaller than the disk-shaped articles to be held in the holder.

The cover 2 is provided at its opposite 60 edges and between its ends with the two spacers or legs 7 arranged at right angles to the cover and resting on the bottom 3. The spacers are preferably integral with the cover and are of such length as to spare 65 the ends of the cover from the ends of the body the required distance to form the slots or openings 8 for the insertion of certain coins, checks, or the like into the holder and into contact with the lower face of the 70 cover. The sides 4 of the body 1 have inwardly extending tongues 9 integral therewith and lying against opposite edges of the cover. The ends of the tongues are bent into recesses 10 in the edges of the cover 75 to hold the cover and body rigidly together. The length of the recesses corresponds to the width of the tongues to prevent the endwise movement of the cover 80 relatively to the body.

The cover has at each end an oval hole or opening 11 beneath which is a cupped or flanged disk or plunger 12 with the cup or flange facing the bottom 3. A coiled spring 13 between each disk and the bottom 3 serve to hold the disks yieldingly 85 against the cover 2 or against the innermost one of any circular articles resting between the disks and the cover. The flanges on the disks are of such depth that 90 the disks can not be removed laterally through the slots 8 when the disks are in contact with the cover. Each spring 13 is arranged in axial alinement with the centers of its adjacent disk 12 and hole 11 and 95 also with the center of an imaginary circle in whose circumference the adjacent rounded end 5 lies. The disks 12 have preferably the same diameter as the articles to be inserted into the holder, but the holes 11 have a 100 slightly smaller diameter to prevent the escape of the said articles through the same. The spacers or legs 7 have their lateral edges arranged to be engaged by the edges of the plungers 12 and of any coins, checks, 105 and the like having approximately the same diameter as the plungers.

When it is desired to deposit a coin in the holder, the proper plunger is depressed and the coin is inserted through the adjacent slot 110

2
and between the cover and the plunger. The adjacent spring 13 causes the coin to be frictionally held against the lower face of the cover. A second coin may be placed 5 on the first coin in a similar manner, and this process repeated until the magazine between the depressed plunger and the cover is entirely filled. The coins are easily removed one at a time through the adjacent 10 slot 8 by inserting the thumb or finger through the proper hole 11 and pushing the coin out in an obvious manner.

I claim:

1. In a holder for disk-shaped articles, an 15 elongated casing comprising a body member and a cover member, there being a slot in each end of one member to admit said articles one at a time into the casing, in combination with legs bent down from the center 20 of the sides of the cover member and resting on the bottom of the body member, and means on the body member for securing both members together, the opposing edges of the legs being spaced less than the diameter 25 of the said articles and disposed at such distances from the ends of the casing as to be engaged by the periphery of the articles when they have been inserted through the 30 said slots into the casing a predetermined distance.

2. In a holder for disk-shaped articles, a casing comprising an elongated dished body member and a cover member, the sides of the body member being spaced apart a distance 35 equal to the diameter of said articles and there being a slot in each end of the casing to admit articles into the casing parallel with the cover member, and there being an opening at each end of the cover of less 40 width than the diameter of an article, a pair of legs integral with the edges of the cover and resting on the bottom of the body member, the edges of the legs being engaged by the articles and serving as stops therefor 45 when they have been pushed through the slots a predetermined distance.

3. In a holder for disk-shaped articles, a casing comprising an elongated dished body member and a cover member, the sides of the body member being spaced apart a distance 50 equal to the diameter of said articles and

there being a slot in each end of the casing to admit articles into the casing parallel with the cover member, and there being an opening at each end of the cover of less width 55 than the diameter of an article, a pair of legs integral with the edges of the cover and resting on the bottom of the body member, the edges of the legs being engaged by the articles and serving as stops therefor when they 60 have been pushed through the slots a predetermined distance, in combination with a spring-pressed plunger beneath each opening in the cover and arranged to clamp an article in registry with the adjacent slot, the 65 said edges of the legs serving as guides for the plungers.

4. In a holder for disk-shaped articles, an elongated casing comprising a body member and a cover member, there being a slot 70 in one end of the casing through which said articles may be passed into the casing parallel with the cover member, a spring-pressed plunger at the slotted end of the casing and arranged to clamp an article in registry with 75 the slot, and a pair of opposed spacers between the cover and body members, the spacers being integral with the opposite edge of the cover and having their edges free and arranged as a stop and guide for the plunger 80 and also for said articles on the plunger.

5. In a holder for disk-shaped articles, an elongated casing comprising a body member and a cover member, there being a slot in one end of the casing through which said articles may be passed into the casing parallel with the cover member, a spring-pressed plunger at the slotted end of the casing and arranged to clamp an article in registry with 85 the slot, and a pair of opposed spacers between the cover and body members, the spacers being integral with the opposite edge of the cover and having their edges free and arranged as a stop and guide for the plunger 90 and also for said articles on the plunger and the cover member having an opening opposite the plunger and elongated in the direction of movement of an article passing 95 through the said slot.

Signed at Pittsburgh, Pa., this 2d day of 100 March, 1921.

JOSEPH J. SZEPE.
